INVENTOR

Frank M. Freeburg

BY ATTORNEY

UNITED STATES PATENT OFFICE.

FRANK M. FREEBURG, OF PHILADELPHIA, PENNSYLVANIA.

RAILWAY SWITCH.

Application filed April 25, 1925. Serial No. 25,807.

To all whom it may concern:

Be it known that I, FRANK M. FREEBURG, a citizen of the United States, residing at Philadelphia, in the county of Philadelphia and State of Pennsylvania, have invented 5 certain new and useful Improvements in Railway Switches, of which the following is a specification.

My invention relates to improvements in 10 railway switches wherein are employed a main rail and a branch rail leading therefrom; said rails comprising main tread and guard surfaces having a groove formed between said surfaces for the wheel flanges, 15 and switch rails, or risers, are provided in said grooves, which are adjustable vertically to the level of the tread surface of the tracks, or lowered to the level of the bottom of said grooves to control the direction of 20 travel of car wheels relatively to the main and branch tracks.

The object of my invention is to provide a 25 novel switch of this character having switch rails which are movable in a novel manner; a further object of my invention is to provide novel mechanism for shifting the switch rails; a still further object of my invention is to provide a switch in which the switch rails are supported upon a rigid base 30 when in either the raised or lowered positions; and a still further object of my invention is to provide means for automatically depressing a switch rail by the action of a car wheel, "trailing", or passing over 35 the switch in the opposite direction from the direction of travel which the switch is intended to control.

With these and other objects in view, my 40 invention consists in the novel construction and combinations of parts hereinafter fully described and claimed.

In the accompanying drawings, illustrating my invention,

Figure 1 is a plan view of a railway 45 switch embodying my invention;

Figure 2 is a vertical longitudinal section on line 2-2 of Fig. 1, drawn on a larger scale;

Figures 3, 4, 5 and 6 are transverse sections of the switch structure, on lines 3-3, 50 4-4, 5-5 and 6-6, respectively, of Fig. 1, drawn on a larger scale;

Figure 7 is a view similar to Fig. 5, showing the switch rails in the reverse positions;

Figure 8 is an enlarged longitudinal section on line 8-8 of Fig. 1.

Referring to the drawings, 12 designates the frame of the switch structure having the main track groove 13 and the branch track groove 15 formed therein, said groove 60 adapted to receive the car wheel flanges in the usual manner. The frame 12 forming the switch structure is provided with main tread portions 17 and 18 forming sections of the main and branch rails of the switch, 65 respectively, and located on the outside of said grooves 13 and 15. The switch structure is also provided with the usual guard portions 19 and 20, extending parallel with said tread portions and located upon the 70 inner side of said grooves 13 and 15. One end of the guard portion 20 of the branch rail converges with the tread portion 17 of the main rail and forms the frog point 21. The outer ends of the main and branch 75 tracks of the switch structure are adapted to be connected with additional rail sections in the usual manner.

Located within the grooves 13 and 15 are switch rails, or risers 22 and 23, respectively, 80 which are movable vertically and guided between the vertical walls of the main and guard portions of the rails. Said switch rail 22 is pivotally mounted upon the frame 12 by links 25 and 26, and the switch rail 23 is pivotally mounted upon the frame by links 28 and 29. Said links are located at opposite ends of each switch bar. Thus the latter will have a circulatory motion and they will always be maintained parallel with 85 the top surface of the main and guard portions of the rails.

The switch rails 22 and 23 are interconnected by operating mechanism so that they 90 will be alternately raised and lowered, whereby the top surface of one switch rail will assume a position on a level with the tread and guard surfaces of the main and branch rails and the other switch rail will assume a position having its top surface on 95 a level with the bottom surface of said grooves 13 and 15.

The frame 12 of the switch is provided with vertical slots 30 and 31 which are occupied by the switch rails 22 and 23. Said 100 slots extend throughout the length of the switch rails and slightly beyond the ends of the latter, to provide for the necessary longitudinal movement of the switch rails. Said slots 30 and 31 are in alignment with 105 the grooves 13 and 15 of the main and branch rails, so that when a switch rail is

depressed into one of said slots, a groove is formed above the switch rail, thus forming a continuation of said grooves 13 or 15, for the passage of the wheel flange over the 5 switch.

The switch rail 22 is pointed at one end and has a vertical wall 33, which latter when the switch rail 22 is raised and the switch rail 23 is lowered, connects with, or forms a 10 continuation of, the vertical wall of the frog point 21 and the vertical wall of the guard portion 19, thus forming a continuous groove between the main track groove 18 and the branch track groove 15, adapted to direct 15 a wheel flange from the main track to the branch track. The top surface of the switch rail 22 when raised is on the same level as the surface of the main tread and guard portions 17 and 19, and also the branch 20 tread and guard portions 18 and 20.

The switch rail 23 is also pointed and has a vertical wall 34, which latter when the switch rail 23 is raised, and the switch rail 22 is lowered, connects with, or forms a continuation of, the vertical wall of the tread portion 17 of the main rail and the vertical wall of the frog point 21 in alignment with the main groove 13, thus forming a continuous groove between the main track grooves 30 13 at opposite ends of the switch, and adapted to direct a wheel flange along the main track and prevent the wheel from following the branch track. The top surface of the switch rail 23 when raised, is on the same 35 level with the tread surfaces of the frog point 21 and of the tread surface 17 of the main track, at opposite ends of the switch, thus forming a continuous tread surface adapted to support a wheel passing over the 40 switch in the line of the main track.

The switch frame 12 is constructed with cross-ribs 36 adapted to support the switch rails 22 and 23. Between said cross-ribs 36, the frame is of open construction, thus the 45 slots 30 and 31, in which the switch rails are positioned, are open at the bottom, with the exception of said cross-ribs 36, permitting dirt and water to pass through the slots and not interfere with the movements of the 50 switch rails. Stones, or bolts, falling upon the top of the switch rails will be lifted above the surface of the rails and will not interfere with the raising and lowering of the switch rails.

55 The mechanism for operating the switch rails 22 and 23 consists of the links 25 and 26 pivotally connected to the switch rail 22 by pins 38 and 39. The links 28 and 29 are pivotally connected with the switch rail 23 60 by pins 40 and 41. The links 25 and 28 located adjacent to the point ends of the switch rails are rotatably mounted upon a shaft 43 secured in bearings 44 and 45 formed upon the switch frame, as shown in Figs. 2 and 4. The links 26 and 29, located at the

heel ends of the switch rails are rigidly mounted upon the square portions of a shaft 46, rotatably mounted in bearings 47 and 48 formed upon the switch frame 12, as shown in Figs. 2 and 6. A segmental arm 50 is secured to one end of the shaft 46, adapted for rocking the shaft to alternately raise and lower the switch rails 22 and 23, into the different positions, as shown in Figs. 5 and 7. Said arm 50 is provided with a socket 51 adapted to have an operating handle 52 inserted therein for operating the switch. A pin 53 is provided upon the arm 50 and forms a point of attachment for a spring 54 which is also connected to a part 55 on the frame 12 located directly below the shaft 46, as shown in Fig. 8, whereby the spring will tend to throw the arm 50 to its extreme positions. Any other well known form of mechanism for shifting the switch may be employed without departing from my invention.

The switch rails 22 and 23 are each supported upon the cross-ribs 36 of the frame 12, when they are either in the raised or lowered positions. Figs. 2 and 5 show the switch rail 23 in the lowered position with its under surfaces 57 resting upon the top of the cross-ribs 36. Each switch rail 22 and 23 is provided with downwardly extending lugs 58 and 59, respectively. The bottom surfaces of said lugs 58 and 59 rest upon the top of the cross-ribs 36, when the switch rails are in the raised position. The switch rail 22 is shown in Figs. 2 and 5, in the raised position, with its lugs 58 resting upon the top of the cross-ribs 36. When the switch is reversed from the position shown in Fig. 2, the links 25 and 28, connected with the switch rails 22 and 23, will move about the shaft 43, and the links 26 and 29 will move about the shaft 46, anti-clockwise. The pivot pins 38 and 39 connecting the links 25 and 26 with the switch rail 22 are positioned slightly to the right of the vertical center lines above the shafts 43 and 46, as shown in Fig. 2. Therefore, the first movement of the links 25 and 26 will tend to lift the lugs 58 of the switch rail 22 off the cross-rib 36, so that the lug 58 will move free of the cross-ribs 36 and permit the switch rail 22 to swing down until its under surfaces 56 rest upon the cross-ribs 36.

Simultaneously with this movement of the switch rail 22 the links 28 and 29 are lifting the switch rail 23. Said links 26 and 29 being rigidly connected upon the shaft 46 will rotate as a unit, anti-clockwise, about said shaft 46, from the position shown in Fig. 2. When the pins 40 and 41 of the links 28 and 29 are directly above the shafts 43 and 46, the lugs 59 will swing clear of the cross-ribs 36 and when said links pass to the left of the vertical center line (Fig. 2) above the shafts 43 and 46 the lugs 59

will rest upon the cross-ribs 36. It will be seen that the switch rails 22 and 23 are supported upon the cross-ribs 36 when in either the raised or lowered positions and the links are thus relieved of any strain due to the wheels passing over the switch.

The switch rails 22 and 23 are provided at their opposite ends with downwardly inclined top surfaces 60 and 61, which bring the extreme ends of the switch rails slightly below the tread surfaces of the main and branch tracks and thus relieve the ends of the switch rails of the load of the wheels as they roll upon the switch rails.

Mechanism is provided for depressing the switch rails 22 and 23 automatically by the action of a wheel passing over the switch in the reverse direction, or what is known as, "trailing the switch". Said shifting mechanism consists of operating dogs 63 and 64, secured upon a shaft 65, pivotally mounted in the switch frame 12. The dog 63 is located in the groove in which the switch rail 22 is located and positioned in alignment with the heel end of the switch rail 22 and with the groove 13 of the main rail. The dog 64 is located in the slot in which the switch rail 23 is located and positioned adjacent to the heel of the switch rail 23 and in alignment with the groove 15 of the branch rail 18. When the switch rail 23 is lowered, the free end of the dog 64 is nearly on a level with the bottom of the groove 15, as shown in Fig. 2, thus permitting the flange of the wheel to pass freely over the dog 64. Figure 2 shows the heel end of the switch rail 22 in dotted lines, in the raised position, and the dog 63 in the raised position, with its highest portion thereof level with the tread surface of the rails. The dog 63, in the raised position, thus occupies a position in alignment with the groove 13 of the main rail. When a wheel passes in the direction of the arrow A, the flange of the wheel will roll upon and depress the free end of the dog 63 and rock the shaft 65.

An arm 67 is rigidly secured upon the shaft 65. A connecting bar 68 pivotally connects the arm 67 with an arm 69 rigidly secured upon the shaft 46. When the shaft 65 is rocked by a wheel flange depressing a dog 63, or 64, the shafts 65 and 46 will be rotated and depress the switch rail which is in alignment with the dog acted upon by the wheel flange, thus allowing the wheel flange to pass over the switch without riding up over the switch rail, due to the switch rail having been thus shifted to the lower position by action of a dog 63 or 64. When one switch rail is depressed, the other switch rail is raised and the dog which is in alignment with the latter rail is also raised. When the switch is operated by the hand lever 52 the dogs 63 and 64 are also op-

erated automatically by the connecting bar 68, as above described.

The frame 12 is provided with webs 70 extending longitudinally for bracing the structure. The slots 30 and 31 formed in said frame for the switch rails 22 and 23 are necessarily longer than the switch rails on account of the longitudinal movements of said rails, and to avoid having these spaces exposed and unoccupied means for filling said spaces are provided, as shown in Figs. 1 and 2. The point of the switch rail 22 is provided with an extension, or finger 71, which extends under the portion 72 of the frame 12, which forms the bottom of the groove 13. Said finger 71 fills the space when the switch rail 22 is raised, as shown in Fig. 2, and when depressed the finger 71 swings under the said portion 72. The frame 12 is provided with an extension 73 located adjacent to the point of the switch rail 23. Said extension 73 fills the space between the end of the switch rail 23 and the portion 72, as shown in Fig. 2. The end of the extension 73 is inclined downwardly to permit the end of the switch rail 23 to ride over the same when said rail 23 is raised. The opposite ends of the switch rails 22 and 23 are provided with downwardly inclined fingers 74 and 75, respectively. Said fingers are adapted to fit closely to the under portions of the dogs 63 and 64, and thus fill the spaces which would otherwise be formed when the switch rails are in their different positions. The dog 64 is provided with an extra arm 76 adapted for filling the space at the end of the switch rail 23.

The operation of my improved switch is as follows:—

When the handle 52 is in the position shown in Fig. 8, the switch rail 22 is in the raised position and the switch rail 23 is depressed, and the dogs 63 and 64 are in corresponding positions. The groove 15 is thus open from the main rail groove 13 through the switch to the branch rail 18. The vertical face 33 of the raised switch rail 22 will direct the flange of a wheel through said groove. Should a wheel pass over the main rail groove 13, in the direction of the arrow A, Fig. 1, the flange of the wheel will depress the dog 63 which will cause the switch rail 22 to be depressed and thus form a free passage for the wheel flange through the groove 13 of the main rail. When the switch is thus shifted by the dog 63 being depressed or by shifting the handle 52 to the reverse position, the switch rail 22 will be depressed and the switch rail 23 and the dog 64 will be raised. The vertical face 34 of the switch rail 23 will direct the flange of a wheel through the switch in the line of the groove 13 of the main rails and prevent the wheel from

passing to the branch track 18. A wheel passing from the branch track 18 in the direction of arrow A will strike the dog 64 and depress the same and thus depress the switch rail 23, thus allowing the wheel to pass over the switch rail 23 without riding upon the same.

My improved switch makes it impossible for the trucks of a car to split and go over the wrong rails of the switch. The switch rails are fully supported upon the frame, thus relieving the operating mechanism of the weight of the wheels; and the usual pivot joints at the heel of the switch rails, such as used heretofore in switches, are eliminated.

I claim:

1. In a railway switch, the combination of a main rail, a branch rail leading therefrom, and a pivoted switch rail movable vertically and longitudinally adapted to control the passage of car wheels relatively to said main and branch rails.

2. In a railway switch, the combination of a main rail, a branch rail leading therefrom, a vertically and longitudinally movable switch rail adapted to control the passage of a car wheel relatively to the main rail and the branch rail, and a member pivotally associated with the switch rail adapted for swinging the switch rail in a vertical plane into the raised and lowered positions relatively to said rails.

3. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch rails.

4. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch tracks, and a bearing part upon said frame adapted to support said switch rail in the raised position and relieve the link of the load of a wheel passing over the switch rail.

5. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch tracks, a transverse rib upon said frame positioned below said switch rail, said switch rail having high and low portions upon the under surface thereof adapted to rest upon said rib, and said link being so positioned that it will lift the switch rail off said rib during its movements and allow said high or low portion of said switch rail to rest upon

tical plane into the raised and lowered positions relatively to said main and branch tracks, and a bearing part upon said frame adapted to support said switch rail in the raised or lowered positions and relieve the link of the load of a wheel passing over the switch rail.

6. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch tracks, and a bearing part upon said frame adapted to support said switch rail in the raised position, and said link being so positioned in relation to its pivotal bearing upon said frame that the initial movement of the link will lift the switch rail off said bearing part of the frame and the final movement of the link will lower the switch rail so that another portion thereof will rest upon said bearing part and support the switch rail in the lowered position.

7. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch tracks, a transverse rib upon said frame positioned below said switch rail, and said switch rail having portions thereof located in different horizontal planes in relation to the plane of the top surface of the switch rail adapted to rest upon said rib when the switch rail is in the raised or lowered position and relieve said link of the load of a wheel passing over the switch rail.

8. A railway switch comprising a main rail, a branch rail leading therefrom, a frame upon which said rails are mounted, a switch rail adapted to control the passage of car wheels relatively to said main and branch rails, a link pivotally associated with said switch rail and with said frame adapted for swinging the switch rail in a vertical plane into the raised and lowered positions relatively to said main and branch tracks, a transverse rib upon said frame positioned below said switch rail, said switch rail having high and low portions upon the under surface thereof adapted to rest upon said rib, and said link being so positioned that it will lift the switch rail off said rib during its movements and allow said high or low portion of said switch rail to rest upon

- said rib when the switch rail is in the raised or lowered positions in relation to said main and branch rails.
9. A railway switch comprising a main rail, a branch rail leading therefrom, a frame upon which said rails are mounted, a switch rail movable vertically and longitudinally adapted to control the passage of car wheels relatively to said main and branch rails, a bearing part upon said frame upon which said switch rail is supported in the raised position, a link having a pivot point upon said frame and a pivotal connection with said switch rail, said link being so positioned that the pivotal connection between the link and the switch rail will pass over and beyond a point directly above said pivot point of the link with the frame whereby the switch rail may be entirely supported upon said bearing part of the frame
10. A railway switch comprising a main rail, a branch rail leading therefrom, a frame upon which said rails are mounted, a switch rail movable vertically and longitudinally adapted to control the passage of car wheels relatively to said main and branch rails, a lug upon the under surface of said switch rail, a bearing part upon said frame upon which said lug is adapted to rest when the switch rail is in the raised position, a link pivotally connecting the switch rail with said frame, and said link being so positioned in relation to its pivot point upon said frame that said lug will swing free of the said bearing part of the frame during the movements of the switch rail.
11. A railway switch comprising a main rail, a branch rail leading therefrom, a frame upon which said rails are mounted, a switch rail movable vertically and longitudinally adapted to control the passage of car wheels relatively to said main and branch rails, a link pivotally connecting the switch rail with the frame, a bearing part upon the frame adapted to support the switch rail in its lowered position, and a lug upon the under side of said switch rail adapted to rest upon said bearing part of the frame when the switch rail is in the raised position.
12. A railway switch comprising a main rail, a branch rail leading therefrom, a frame upon which said rails are mounted, switch rails adapted to control the passage of car wheels relatively to said main and branch rails, a shaft rotatably mounted in said frame, links having one end thereof rigidly mounted upon said shaft and pivotally associated with said switch rails at their opposite ends, and said links being arranged upon said shaft in different radial positions whereby the switch rail connected upon one of said links will be in the raised position and the other switch rail will be in the lowered position in relation to said main and branch rails.
13. A railway switch comprising a main rail, a branch rail leading therefrom, a frame upon which said rails are mounted, switch rails adapted to control the passage of car wheels relatively to said main and branch rails, a shaft rotatably mounted in said frame, links having one end thereof rigidly mounted upon said shaft and pivotally associated with said switch rails at their opposite ends, said links being arranged upon said shaft in different radial positions, and an arm secured upon said shaft adapted for rocking the latter for simultaneously swinging the switch rails upon said links into the raised and lowered positions relatively to the main and branch rails.
14. A railway switch comprising a main rail, a branch rail leading therefrom, a frame upon which said rails are mounted, switch rails adapted to control the passage of car wheels relatively to said main and branch rails, a shaft rotatably mounted in said frame, links having one end thereof rigidly mounted upon said shaft and pivotally associated with said switch rails at their opposite ends, an arm secured upon said shaft adapted for rocking the same for raising and lowering the switch rails by swinging said links into different radial positions, and a spring interposed between said arm and said frame tending to move said arm in either direction from a central position in relation to said shaft.
15. A railway switch comprising a main rail, a branch rail leading therefrom, a frame upon which said rails are mounted, switch rails adapted to control the passage of car wheels relatively to said main and branch rails, a shaft rotatably mounted in said frame, links having one end thereof rigidly mounted upon said shaft and pivotally associated with said switch rails at their opposite ends, said links being arranged upon said shaft in different radial positions, and a bearing part upon said frame adapted to support the switch rails in the raised or lowered positions relatively to the main and branch rails.
16. A railway switch comprising a main rail, a branch rail leading therefrom, a frame upon which said rails are mounted, switch rails adapted to control the passage of car wheels relatively to said main and branch rails, a shaft rotatably mounted in said frame, links having one end thereof rigidly mounted upon said shaft and pivotally associated with said switch rails at their opposite ends, said links being arranged upon said shaft in different radial positions, bearing parts upon said frame adapted to support a switch rail when in the lowered position, and a lug upon the under side of each switch rail adapted to rest upon said bearing part when a switch rail is in the raised position.

17. A railway switch comprising a main rail, a branch rail leading therefrom, a frame upon which said rails are mounted, a switch rail adapted to control the passage of car wheels relatively to said main and branch tracks, and links pivotally associated with opposite ends of said switch rail and pivotally mounted upon said frame adapted for swinging the switch rail in a vertical plane into the raised and lowered positions and maintain said switch rail in parallel relation with the upper surface of the main and branch rails. 70
18. A railway switch comprising a main rail, a branch rail leading therefrom, a frame upon which said rails are mounted, switch rails adapted to control the passage of car wheels relatively to the main and branch tracks, links pivotally connected with the switch rails adjacent to the points thereof, a shaft mounted in the frame upon which said links are pivotally mounted, links pivotally connected with the opposite ends of said switch rails, and a shaft rotatably mounted in the frame upon which the last mentioned links are rigidly secured in different radial positions whereby one switch rail will be in the raised position when the other switch rail is in the lowered position. 80
19. A railway switch comprising a main rail, a branch rail leading therefrom, a frame upon which said rails are mounted, a switch rail adapted to control the passage of car wheels relatively to said main and branch tracks, links pivotally connected with said switch rail at opposite ends thereof, bearings in said frame in which said links are pivotally mounted, and means for moving the switch rail upon said links to raise and lower the switch rail. 90
20. A railway switch comprising a main rail, a branch rail leading therefrom, a frame upon which said rails are mounted, a switch rail adapted to control the passage of car wheels relatively to said main and branch tracks, links pivotally connected with said switch rail at opposite ends thereof, bearings in said frame in which said links are pivotally mounted, transverse ribs upon said frame adapted to support said switch rail in a horizontal position when swung upon said links into the raised position relatively to the main and branch rails. 100
21. A railway switch comprising a main rail, a branch rail leading therefrom, a frame upon which said rails are mounted, a switch rail adapted to control the passage of car wheels relatively to said main and branch tracks, links pivotally connected with said switch rail at opposite ends thereof, bearings in said frame in which said links are pivotally mounted, transverse ribs upon said frame adapted to support said switch rail in a horizontal position when lowered relatively to the main and branch rails, and 110
22. A railway switch comprising a main rail, a branch rail leading therefrom, a frame upon which said rails are mounted, a switch rail adapted to be raised and lowered to control the passage of car wheels relatively to the main and branch rails, a part located adjacent to one end of the switch rail adapted to be depressed by a car wheel passing over said part, and mechanism operatively associated with said part and with said switch rail adapted to depress the latter when said part is depressed. 120
23. A railway switch comprising a main rail, a branch rail leading therefrom, a frame upon which said rails are mounted, a switch rail adapted to be raised and lowered to control the passage of car wheels relatively to the main and branch rails, a part located adjacent to one end of the switch rail adapted to be raised and lowered simultaneously with the switch rail, and said part located, when in the raised position, in the path of a car wheel and adapted to depress the switch rail when acted upon by the car wheel. 130
24. A railway switch comprising a main rail, a branch rail leading therefrom, a frame upon which said rails are mounted, a switch rail adapted to be raised and lowered to control the passage of car wheels relatively to the main and branch rails, a dog pivotally mounted in said frame, said dog positioned adjacent to one end of the switch rail and adapted to be engaged by a car wheel approaching the switch rail, and mechanism operatively associated with the dog and the switch rail adapted for simultaneously raising or lowering the dog and the switch rail. 140
25. A railway switch comprising a main rail, a branch rail leading therefrom, a frame upon which said rails are mounted, a switch rail adapted to be raised and lowered to control the passage of car wheels relatively to the main and branch rails, a dog pivotally mounted in said frame adjacent to one end of the switch rail and in the path of a car wheel approaching the switch rail when in the raised position, a link pivotally connecting the switch rail with the frame, an arm upon said link, an arm upon said dog, and a connecting bar connected between said arms adapted to raise or lower the switch rail and the dog simultaneously. 150
26. A railway switch comprising a main rail, a branch rail leading therefrom, a frame upon which said rails are mounted, a switch rail adapted to be raised and lowered to control the passage of car wheels relative- 160

- ly to the main and branch rails, a dog pivotally mounted in said frame, said dog positioned adjacent to one end of the switch rail and adapted to be engaged by a car wheel 5 approaching the switch rail, mechanism operatively associated with the dog and the switch rail for simultaneously raising or lowering the switch rail and the dog, a link pivotally associated with the frame and the switch rail upon which the latter is raised or lowered, and an extension upon the switch rail adapted to extend under the dog and occupy the space between the dog and the switch rail when the latter is in the raised position.
27. A railway switch comprising a main rail, a branch rail leading therefrom, a frame upon which said rails are mounted, switch rails adapted to control the passage 20 of car wheels relatively to the main and branch tracks, links pivotally connected with the switch rails adjacent to the points thereof, said links pivotally mounted upon said frame, links pivotally connected with the heel end of each switch rail, a shaft rotatably mounted in the frame upon which the last mentioned links are rigidly secured in different radial positions whereby one switch will be in the raised position when 30 the other switch is in the lowered position, dogs located adjacent to the heel end of each switch rail, a shaft rotatably mounted in the frame upon which said dogs are secured in different radial positions adapted to 35 be depressed by a car wheel approaching the switch rails and mechanism for rocking the shaft carrying the dogs simultaneously with the shaft carrying said links connected with the heel end of the switch rails.
40. 28. A railway switch comprising a main rail, a branch rail leading therefrom, a frame upon which said rails are mounted, a switch rail adapted to be raised and lowered to control the passage of car wheels relatively 45 to the main and branch rails, said frame having a slot formed therein adapted to be occupied by the switch rail, a link pivotally connected with the switch rail and said frame upon which link the switch rail is adapted to swing in a vertical plane and overlap the portion of the frame located adjacent to the end of the slot.
29. A railway switch comprising a main rail, a branch rail leading therefrom, a frame upon which said rails are mounted, 55 switch rails adapted to control the passage of car wheels relatively to said main and branch rails, links pivotally connected with said switch rails and with said frame adapted for swinging the switch rails into 60 the raised and lowered positions, said frame having slots formed therein adapted to be occupied by said switch rails, a finger upon one switch rail adapted to extend under the frame adjacent to the end of said slot, and 65 a finger upon said frame adapted to extend under the other one of the switch rails.
30. A railway switch comprising a main rail, a branch rail leading therefrom, a frame upon which said rails are mounted, 70 switch rails adapted for controlling the passage of car wheels relatively to the main and branch tracks, said frame having slots formed therein in which said switch rails are positioned, links pivotally associated with 75 said frame and with opposite ends of the switch rails adapted for swinging the switch rails into the raised and lowered positions relatively to the main and branch rails, cross ribs upon the frame adapted to support said switch rails when in the lowered positions, lugs upon said switch rails adapted to rest upon said ribs when the switch rails are in the raised position, a shaft rotatably mounted in said frame to which a 80 link of each switch rail is secured in a different radial position adapted for simultaneously raising one switch rail and lowering the other switch rail, a part positioned adjacent to the end of each switch rail, and 85 means operatively connecting said parts with said shaft adapted for depressing a switch rail when one of said parts is acted upon by a car wheel approaching a switch rail.

In testimony whereof I affix my signature hereto.

FRANK M. FREEBURG.
